UNITED STATES PATENT OFFICE.

JOHN STUART BIGGAR, OF CHICAGO, ILLINOIS, ASSIGNOR TO MARY E. H. RUTTER, OF SAME PLACE.

ELECTRICAL CIRCUIT FOR OPERATING AUTOMATIC RAILWAY-GATES.

SPECIFICATION forming part of Letters Patent No. 576,493, dated February 2, 1897.

Application filed January 22, 1895. Serial No. 535,764. (No model.)

To all whom it may concern:

Be it known that I, JOHN STUART BIGGAR, residing at Chicago, Cook county, Illinois, have invented an Electrical Circuit for Operating Automatic Railway-Gates, of which the following is a specification.

My invention has special reference and application to that class of railway-gates either of the gravity, electric, or pneumatic type 10 designed to be automatic in action by the movements of trains upon the track, and I will describe it in connection with automatic gates, therefore, for convenience.

In general terms the means consist of a 15 novel disposition of electrical devices and circuits for automatically controlling the lowering of the gates and also for ringing an alarm. I provide for the lowering of the gates when the train approaches to within a predetermined distance and for the raising of the 20 gates only after the last car has entirely cleared the crossing or other point, regardless of the length of the train, as the mechanism is controlled by the last truck of the last car. 25 I also embody other novel and advantageous features which will be apparent from the description of the invention as hereinafter set forth; and my invention consists in the features and details of construction herein- 30 after described and claimed.

In the drawings, Figure 1 is an elevation, partly in section, of one form of gate-operating mechanism which is under the control of my electrical devices and operates in connection therewith; Fig. 2, a diagrammatic view of the electromagnets and circuits; Fig. 3, a detail of one of the magnets and its armature, and Fig. 4 a diagrammatic view of a modified arrangement of circuit and electro- 40 magnets.

For the purpose of explaining my invention I have selected the operating mechanism shown in Fig. 1, which is of the type known as "pneumatic," but on this construction I 45 make no claim. This mechanism is under control of electrical devices which constitute my invention, as hereinafter set forth.

I prefer to use a tank A, communicating with a suitable source of compressed air and 50 provided with a feed-pipe A', which connects with the ordinary fluid-pressure-actuated

mechanism in the gates. An exhaust-pipe A² connects with the feed-pipe, and both the exhaust and feed pipes are provided with suitable valves or cocks a a', respectively, which 55 are so connected by a rod a² that when one valve is open the other is necessarily closed. This rod actuates the valves through bell- 60 cranks a³ a⁴, whose free arms are connected to rods a⁵ a⁶, which are operated as follows:

Upon a suitable support I mount a guide-frame B, in which travels a weight B', attached to a piston-rod b. At one side of the guide-frame I provide a catch or dog B², adapted to project below the weight when raised. At a 65 somewhat higher plane I arrange a similar dog B³, adapted to project above the weight when in its lowered position. Arranged vertically below the weight is a barrel B⁴, provided at one side with a rack of teeth b'. 70 This barrel contains a compressible spring B⁵, abutting at its ends, respectively, against the bottom of the barrel and against the piston-head or disk b², adapted to travel in the barrel against the tension of the spring. This 75 disk is provided with a rod b³, adapted to bear against the weight thereabove.

Mounted upon the frame are four vertical rods C C' C² C³, arranged in pairs on either side of the mechanism just described. The 80 rod C has a sliding weight c, while in its path is arranged a trip mechanism consisting of a lever C⁴, held in a normally horizontal position by a spring. Opposite the ratchet-teeth on the barrel is a block C⁵, provided with 85 corresponding teeth. This block is kept in normal engagement with the barrel by means of a spring, but may be released by the downward movement of the lever which withdraws the block by the contact of the upwardly-projecting arm c', bearing against a stud upon the block. An operating-rod C⁶ connects the dog B² to the lever and is adapted to release the former from engagement when the latter is depressed. The rod C² is provided with a 90 similar weight c², adapted to strike in its descent a lever C⁷, and an operating-rod C⁸, similar to rod C', is adapted to actuate the dog mechanism B³.

A device for lifting the tripping-weights is 100 provided consisting of a rocking beam D, pivoted in the upper portion of the guide-frame.

The ends of the beam carry similar rods D'D², having pivoted at their ends sleeves d d', adapted to slide on the guide-rods C' and C³, respectively. Each sleeve carries a laterally-projecting arm d² or d³, projecting in the path of its respective tripping-weight.

Secured to the beam at one side of its pivotal point is an arm D³, having its other end secured in an adjustable manner to the vertical rod b. In order to lock the beam in the position shown in Fig. 1, I provide an arm d⁴, having a shoulder adapted to engage the arm d². A rock-shaft D⁴, connected to suitable tread-levers on a railway-track, (not shown,) is mounted in the frame and carries an arm D⁵ in contact with the bottom of the barrel.

Electromagnets E E' are located adjacent to the weights c c² in such position that their pivoted armatures e e' will project in the path of the weights and serve to support them when said weights are elevated by the beam mechanism.

Before proceeding to set forth the electrical circuit, appliances, &c., of which the magnets E E' form a part, I will explain the operation of the mechanism above described. Assuming that a train is approaching a crossing, it will close a circuit and thereby energize magnet E, attracting its armature and allowing the weight c to drop. The lever C⁴ will thereby be depressed, withdrawing the block C⁵ from engagement and simultaneously thrusting the rod a⁵ downward, opening the valve a and closing valve a', whereby air-pressure is supplied to the gate-cylinder and the exhaust closed. The gates are now lowered.

Simultaneous with the withdrawal of the block the dog mechanism B² is operated by the lever and the weight B' allowed to drop, being held in its lower position by the dog B³. The spring is thereby compressed somewhat in the barrel, and by the lowering of the rod b the beam D is operated and the weight c is raised back to its normal position, while the lifting device on the other side is lowered to allow free descent of the weight c² when it is time for it to act. When the train passes over the track-lever near the crossing, the shaft D⁴ will be rocked and the barrel forced upward against the tension of the inclosed spring. The lever C⁴ is kept in its lowered position by the dog B², which is forced to the right, Fig. 1.

When the train has cleared the crossing, it will close another circuit and cause the magnet E' to attract its armature, and thereby allow the weight c² to drop. The lever c⁷ is thereby depressed and the valve a closed and the exhaust a' opened, whereby the gate-cylinder will exhaust back through the pipe A². At the same time the dog B³ is withdrawn and the tension of the barrel-spring will force the weight B' upward and also rock the beam and carry the tripping-weight c² and support it in the position shown.

Considering Fig. 2 of the drawings, I have

shown for the purposes of a full understanding of the invention a double-track railway, although my invention is applicable to a simple single-track line. That portion of track in the neighborhood of the crossing and gates is divided up into insulated sections in the following manner: At a predetermined distance from the right of the crossing, Fig. 1, say about fifteen hundred feet or more, an insulation f is interposed in the rail F, and at a distance of about, say, one hundred and fifty feet nearer the crossing insulations f' f² are arranged, respectively, in the rails F and G. Section f³ of rail F thereby becomes isolated. At either side of the crossing insulations G' G² form an isolated section of rail g³ in rail G and extending over the crossing. To the left of the crossing insulations x y z are provided, similar in location to f' f². Section x' is thus similar to f³, and there are also formed rail-sections g' and g² in rail G. The rails H H' are understood to be correspondingly provided with insulations.

A wire 1 is electrically connected to insulated section f³, and communicates through wire 3 with an ordinary electric bell J and battery J', back through wires 4 and 2, and thence through track-connector K, the space from rail to rail being understood to be bridged by the wheels and axles of a car as it enters upon the section. A similar bell-line extends from section x' through wires 1' and 3, bell-wires 4 and 2', and thence through the track-connector K'. These circuits will be hereinafter termed for convenience the "bell-circuits."

The wire 2 is connected to rail-section g² and forms a portion of the main operating circuit composed of wires 2 and 5, branching at point 5' into two shunts, one connected to the coil of an electromagnet L, and extending by wires 6 and 7 to battery J². The other shunt is connected to an ordinary circuit-breaker K² by wire 8 and is connected by wire 8' to the coil of electromagnet E. The shunts then unite at 7' and extend to the battery and thence by wire 9 to rail F. This circuit will be hereinafter designated for convenience the "right-hand main circuit."

The main wire 2' is connected to rail-section g' through magnets L and E, and thence to rail F, as before. This circuit may be termed the "left-hand main circuit." In both instances the wheels and axles of cars complete the circuit from opposite rails.

The wire 10 is electrically connected to section g³ and is a portion of a circuit which extends through the coil of magnet M, through wires 11, 6, and 7, battery J², and wire 9 to rail F. This circuit may be designated the "street" or "crossing" circuit. Operating in connection with this circuit is what I term a "local" circuit, comprising magnet E', wires 12 and 7 to battery J², and wires 9 and 13 through circuit-closer M', circuit-breaker N back to magnet E' by wire 14. The electro-magnet L is provided with a pivoted arma-

ture l , carrying at one end a wedge of insulating material adapted to enter in between the flexible springs of the circuit-breaker K^2 when the armature is attracted and thereby break the circuit of magnet E . It is obvious, therefore, that when any current is passing in the main circuits, either through lines 2 or $2'$, it will pass through both shunts for an instant, sufficient to attract the armature of magnet E , after which the circuit in this shunt will be broken and the entire current pass through the shunt of magnet L , keeping its armature continually attracted.

The magnet M is provided with a pivoted armature m , whose free ends are adapted to operate the circuit-closer M' and circuit-breaker N , respectively. The construction of these parts is detailed in Fig. 3. The circuit-breaker consists of two flexible plates or springs $n\ n'$, separated by insulation, but affording a path for the current through studs $n^2\ n^3$ on the plates, respectively, and normally in contact. On one of the free ends of the armature a point n^4 of insulating material, is secured, so that as the armature is attracted the point will be rocked downward to separate the contact points or studs. The spring n is a continuation of wire 13, while spring n' is connected to line 14.

The circuit-closer consists of a vertical weighted rod M' , having an arm m' , under which the right-hand end, Fig. 1, of the armature engages. The local circuit is normally open at points $O\ O'$. Upon the rod M' is arranged at the proper place a bar O^2 , of conducting material, whereby as the armature lifts the rod the bar will span the break in the circuit and complete it. In order to lock the rod in its upper position and to release it at the proper time, I provide the rod with a shoulder m^2 , in which a spring-pressed arm m^3 engages. In order to throw this arm out of engagement, I provide a plunger m^4 , normally kept in a retracted position by a light weight and adapted to be engaged by the end of the armature, whereby the plunger will be advanced to throw out the arm m^3 . The rod M' will then be free to drop by reason of its own gravity. In this connection it will be observed from the arrangement of the parts that when the magnet is excited the circuit-breaker is actuated slightly in advance of the circuit-closer and that when it is demagnetized the bar O^2 will for an instant span the points after the contact of the studs $n^2\ n^3$, thereby momentarily completing the local circuit.

The circuits and operating parts being arranged as above set forth, I will now proceed to describe my method and the operation of the gates.

Assuming that a train is approaching on the upper track from the right, Fig. 2, it will enter the insulated section f^3 and by means of the wheels and axles of the cars will complete the bell-circuit and sound the warning-alarm. As soon as the train has reached sec-

tion g^2 a circuit will be completed through the right-hand main circuit, composed of wire 2, the two shunts containing, respectively, magnets L and E , battery J^2 , and wire 9 to rail F , and thence through the axles and wheels forming a bridge connection between the opposite rails. The armature l will therefore be attracted and the circuit through the other shunt will be broken, but not before the magnet E has become sufficiently energized to attract its armature to allow the weight c to drop and thus operate the gate-arms in the manner before described. 80

It is to be noticed that the bell-circuits are so arranged that the bell is ringing continually while the train is within the danger limit on either side of the crossing. When the train is on section g^2 , the bell is located in a shunt composed of wires 2, 4, 15, and 8 to point $5'$, where it unites with the main circuit running back to rail F .

When the train has reached the crossing and entered section g^3 , it will complete the crossing-circuit in a similar manner. The magnet M thereby becomes energized and remains in that condition as long as there is a truck upon the crossing-section. The armature m is attracted, breaking the local circuit and electrically bridging the space between points $O\ O'$. The local circuit is therefore completed at one point but previously broken at another. When the last truck of the last car has cleared or passed over section g^3 , the crossing-circuit will be broken and magnet M thereby become demagnetized, whereby its armature will drop and for an instant of time the local circuit will be completed. Magnet E' is consequently momentarily excited and the gate mechanism caused to operate so as to raise the gates, as before described. It is to be observed that regardless of the length of the train the gates are not allowed to rise until the last truck has entirely cleared the crossing. It is also to be noticed that the armature of magnet L is still attracted and the shunt through magnet E is broken until the last truck has passed beyond section x' , whereby the weight c is kept in its normal position. 105

As shown in Fig. 2, the set of rails $H\ H'$ of the other track is properly connected in the circuits, so as to permit trains to operate the gate mechanism in precisely the same manner 120 as upon the other track. It will be understood, however, that a train passing on the upper track from left to right, Fig. 2, will operate the gates the same as when going in the opposite direction. 125

In Fig. 4 I have shown a modified form of circuit in which the mechanism of Fig. 1 may be dispensed with, but in which fluid-pressure is supplied to the gate mechanism in the same way. The rails $P\ P'$ are divided up in sections p, p', p^2, p^3 , and p^4 . For convenience I have omitted the bell and its circuits, as it will be obvious that a circuit similar to that shown in Fig. 2 may be provided. The sec-

- tion p forms part of a circuit composed of wires 16 and 17, through points v v' and a portion of armature p^5 of magnet P^2 , wire 18, circuit-breaker P^3 , wire 19, through magnet 5 R , wire 20 to battery Q by wire 21, through wires 22, 23, 24, and 25 to rail P' in section p . The circuit of which section p^2 forms a part consists of wire 26 from rail P , magnets R' and P' , wires 27 and 21 to battery, thence 10 through wires 22, 23, and 28 to rail P' . The circuit in which section p^4 is interposed consists of wire 29 from rail P and the same circuit used by section p , except that it returns to the rail by wire 30.
- 15 The magnet V is provided with a pivoted armature V' , having a wedge V^2 of insulating material at one end and adapted to act upon the circuit-breaker P^3 . The other end of the armature is provided with a shoulder adapted 20 to be engaged by the free end of a pivoted armature p^5 . The latter armature electrically bridges the space between the two separated points of buttons v v' , which are thus connected when the magnet P^2 is demagnetized.
- 25 The armature V' is kept in its normal position (shown in Fig. 4) by means of a light spring v^2 , which will cause the ends of the two armatures to engage when magnet P^2 is excited. The magnet V is interposed in a high-resistance circuit composed of wires 29 and 17 from rail P , wire 38 to magnet, wires 39, 27, and 21 to battery, and thence by wires 22, 23, 24, and 30 to opposite rail P' .
- 35 The magnets S and S' are arranged close together with their similar poles oppositely disposed. They are provided with a common armature S^2 , preferably adjustably secured upon a connecting-rod s , which controls two valves s' s^2 in a manner similar to the rod a^2 40 in Fig. 1. The valve s' in the feed-pipe S^3 is open when the valve s^2 in the exhaust-pipe S^4 is closed, and vice versa. These magnets are arranged in independent local circuits, the magnet S being arranged in a circuit composed of wires 31 and 22, battery, wire 32, circuit-breaker T , wire 32', circuit-closer T' , wire 33, back to magnet. The circuit of magnet S' consists of wires 34 and 22, battery, wire 35, circuit-breaker U , wire 36, circuit-closer U' , and wire 37, back to magnet.
- 45 It will be understood that the construction of the circuit-closers T' and U' is practically identical with that detailed in Fig. 3, while their actuation by means of the armatures rr' 50 is identically the same. The circuit-breakers P and U are of the ordinary construction and operate in the ordinary way.
- 55 Assuming that a train is approaching the crossing which is located at section p^2 , it will 60 enter upon section p and complete the circuit between the rails by means of the wheels and axles. The circuit of this section being thus closed, a current will pass through magnet R and energize it, attracting its armature. The 65 circuit-closer will complete the local circuit of magnet S at one point, but break it at another. As soon, however, as the last truck

has cleared section p the circuit of that section will be broken and the local circuit momentarily closed, whereby the armature S^2 70 will be attracted and reciprocated to the left, Fig. 4, and thus admit air-pressure to the gate-cylinder to lower the gates.

When the first wheels enter section p^2 , the circuit of that section will be completed and 75 the current will pass through magnets R' and P' . The local circuit of magnet S' will then be put into proper position to be completed when the last truck clears the crossing or other predetermined point. Simultaneously 80 the magnet P^2 is excited and its armature attracted, thereby breaking the circuit between points v v' . The armature V' will then engage armature p^5 and withhold it until magnet V is excited to release the parts, as hereinafter described. When the last truck clears the crossing or passes from section p^2 , the local circuit of magnet S' will be completed for an instant and the magnet will be momentarily excited, so as to reciprocate armature 85 S' to the right, Fig. 4, whereby the exhaust-valve will be opened and the supply-pipe valve closed to allow the gates to rise. When the train enters section p^4 , it will complete the circuit of magnet V , which will be energized to attract its armature and thereby release the engaging parts. It is obvious that in this case also a train will properly operate the gates when going in either direction on the same track, and, furthermore, that the 90 operation by trains running on the other set of rails will be precisely the same. In both of the circuits herein shown I have so arranged the circuits and other parts that a single battery is sufficient for the gate-operating mechanism proper.

It will be understood that the core of a solenoid may be attached to the arm of a gravity-gate and the current through the solenoid be automatically under the control of the 110 trains. A circuit somewhat similar to that shown in the drawings may be provided for the purpose.

Although I have described more or less precise forms and details of construction I do 115 not intend to be understood as limiting myself thereto, as I contemplate changes in form, proportion of parts, and the substitution of equivalents as circumstances may suggest or render expedient and without departing from the spirit of my invention.

I claim—

1. In an automatic railway-gate system, the combination, with gate-operating mechanism, of two electrical circuits successively closed 125 by the movements of a car to close and open the gate, and an intervening circuit, also closed by the car, which holds the second circuit open until the entire train has passed a predetermined point.

2. In an automatic railway-gate system, the combination, with gate-operating mechanism, of two electrical circuits successively closed 130 by the movements of a car, electromagnets

interposed in the circuits and adapted to control the gate-operating mechanism to close and open the gate whenever their respective circuit is closed, and an intervening circuit 5 also closed by the car, which holds the second circuit open until the entire train has passed a predetermined point.

3. In an automatic railway-gate system, the combination, with gate-operating mechanism, of a railway-track divided into three insulated sections, the second or middle section being located at the roadway or crossing guarded by the gate, and the first and third sections being located on either side of the crossing or 15 second section, said first and third sections being used in connection respectively with the lowering and raising of the gate, two electrical circuits connected respectively to said first and third sections and successively closed 20 by the movements of a car to control the gate-operating mechanism to close and open the gate and an intervening circuit connected to the second or crossing section and also closed by the car, which intervening circuit holds 25 the second circuit open until the entire train has passed a predetermined point.

4. In an automatic railway-gate system, the combination, with gate-operating mechanism, of a railway-track divided into three insulated 30 sections, the second or middle section being a crossing-section extending over the road or crossing and the first and third sections being located on either side of the crossing-section, an electrical circuit connected to the first section 35 and permitted to be closed by the movements of a car, an electromagnet interposed in said circuit and adapted to permit the gate-operating mechanism to lower the gate, a second electrical circuit connected to the third 40 section and permitted to be closed by the movements of the car, an electromagnet interposed in said last-named circuit and, when closed, adapted to permit the gate-operating mechanism to open the gate, and an intervening 45 circuit connected to the second section of track and also closed by the car, which intervening circuit holds the second circuit open until the last truck of the car has passed off from the crossing or second section.

5. In an automatic railway-gate system, the combination of a railway-track having insulated sections, an electromagnet arranged in a normally open circuit which is permitted to be closed as a car enters a section, mechanism 55 under control of the electromagnet for actuating the gates whereby as the magnet is excited the gate-arms will be lowered, a second electromagnet arranged in a normally open circuit and permitted to be closed only when 60 a car leaves another section at or near the crossing, and a connection with the gate mech-

anism and under the control of the second electromagnet whereby as the latter is excited the gate mechanism will be operated to raise the gate-arms, but only after the last truck 65 of the car has cleared the crossing or other predetermined point.

6. In an automatic railway-gate system, the combination of a magnet arranged in a normally open circuit, means for closing the 70 circuit by the movement of a car upon the railway-track, mechanism for actuating the gates, a connection with the gate mechanism, and under the control of the magnet, whereby as the latter is excited the gate-arms will be 75 lowered, a second magnet arranged in a normally open circuit, means for closing the same as a car reaches the crossing, a third magnet arranged in a local circuit and under the control of the second magnet, whereby 80 as the second magnet is excited and then is demagnetized as the last truck clears the crossing or other point the local circuit will be momentarily completed, and a connection with the gate mechanism and under the control of the third magnet whereby as the latter is excited the gate-arms will be raised.

7. In an automatic railway-gate system, the combination of a railway-track having insulated sections f^3 and g^3 , an electrical circuit 90 normally open at the rails, magnets L and E interposed therein, but each arranged in its own shunt, a circuit-breaker in the shunt of magnet E, a connection between the armature of magnet L and the circuit-breaker 95 whereby as magnet L is excited the shunt-circuit of magnet E will be broken but only after the momentary energizing of the latter magnet, mechanism under control of magnet E for actuating the gates whereby as a car 100 enters section f^3 and completes the circuit magnet E will be excited and the gate-arms lowered, an electrical circuit normally open and connected with section g^3 located at or near the crossing, a magnet M arranged in 105 this circuit, a magnet E' arranged in a normally open local circuit, and a circuit-breaker and a circuit-closer arranged in the local circuit and under control of magnet M whereby as a car enters section g^3 the circuit will be 110 completed and magnet M excited to operate the circuit-breaker and closer, thereby causing the local circuit to be momentarily closed as the last truck of the car leaves section g^3 , and a connection with the gate mechanism 115 under control of magnet E' whereby as the same is excited thus momentarily the gate-arms will be raised.
